UNITED STATES PATENT OFFICE.

WILLIAM TISCH, OF LA CROSSE, WISCONSIN.

BOX-FASTENER.

No. 857,217.

Specification of Letters Patent.

Patented June 18, 1907.

Application filed April 4, 1906. Serial No. 309,887.

To all whom it may concern:

Be it known that I, WILLIAM TISCH, a citizen of the United States, residing at La Crosse, in the county of La Crosse and State of Wisconsin, have invented new and useful Improvements in Box-Fasteners, of which the following is a specification.

This invention relates to box fasteners.

One object is to provide an exceedingly simple, inexpensive, durable and efficient fastening for application to various types of boxes.

Another object resides in the provision of a box fastener embodying such characteristics that it may be positively locked against unfastening and effect a tight closure between the lid and the box proper.

With these and other objects in view the invention consists in the construction, combination and operative aggroupment of parts all as will be more fully described herein-after, illustrated in the accompanying drawings and finally pointed out in the appended claims.

25 In the drawings: Figure 1 is a perspective view of a box illustrating one form of my invention applied thereto, the dotted lines indicating the position of the head of the keeper when the lid is positively locked upon the box. Fig. 2 is a transverse sectional view through the fastener illustrated in Fig. 1, including a portion of the box. Fig. 3 is a detailed view of the keeper plate. Fig. 4 is a perspective view of a modification showing 30 the fastener applied to a box with a raised cover. Fig. 5 is a perspective view of the latch member detached. Fig. 6 is a perspective view of the keeper and its attaching plate.

40 Referring now more particularly to the accompanying drawings the reference character 1 indicates a box provided with a hinged lid 2, the hinge connection being of any character and indicated at 3.

45 In order to hold the lid 2 in tight engagement with the upper edges of the sides and ends of the box 1, I provide a T-shaped keeper plate 4 which is secured to the box 1 at any suitable point by means of fastenings 5. The

50 tail 6 of the keeper plate 4 is bent or upset to form a loop 7 intermediate the ends of the said tail portion 6 to receive the eye 8 in one end of the latch 9, there being a short longitudinal slot 10 formed in the latch member 9

55 to permit of the passage therethrough of the head 11 of a T-shaped keeper 12, which lat-

ter is swiveled in the head of the keeper plate 4. The free end of the latch member 9 is bent, turned or otherwise formed to provide a lip 13 designed to engage the upper face of 60 the lid 2 to bind the latter in close engagement with the box proper.

To fasten the lid upon the box the head 11 of the keeper is turned so that it may aline with the slot 10 of the latch 9 to permit the 65 lip 13 of the latch to engage the upper face of the lid of the box. When the latch has been disposed in the manner just stated, the keeper 12 is turned to present its head 11 transversely of the latch and consequently 70 out of alinement with the slot 10 of the latter, positively fastening the lid tightly upon the box. As clearly shown in the drawings, especially in Fig. 2, the keeper plate is 75 pressed or otherwise forced outwardly to form a seat *a* for the base *b* of the keeper 12, and also to project into the recess *c* of the latch member. This arrangement permits 80 and insures a tight binding action between the inner face of the keeper head 11 and the bulged portion of the latch member formed 85 as the result of producing the seat *a* referred to immediately above. It will thus be understood that even when the head of the keeper is in alinement with the slot 10 of the latch 9 the lip 13 of the latter will serve to 90 hold the lid in its closed position under normal conditions and that a positive fastening is effected by simply turning the keeper 12 in the manner stated.

The fastening hereinbefore described is easily adjusted and effects a positive locking connection between the lid and the box and in the event of the application of my improved fastening to a box provided with a 95 raised lid; that is to say, a lid 14 whose upper face is above the plane of the lip 16, as in Fig. 4, I prefer to dispose a slotted plate 15 along the corresponding face of the lid to receive the lip 16 of the latch 17. With the exception of the slotted plate 15, which is an addition to the aforesaid structure, the modified form of the invention is the same as that first herein described.

As shown in Fig. 6 the keeper may be 105 formed by a blank of suitable material provided with reduced ends and bent upon itself to form the head 11 and shank 12 with a disk 18 fitted upon the shank and the reduced end of the blank forming the shank bent, as 110 at 19, to retain the disk upon the shank.

Having thus described my invention what

I claim and desire to secure by Letters Patent is:—

1. The combination with a box provided with a hinged lid, of a keeper plate provided with upper and lower outwardly directed portions, a latch member pivoted at one end to the lower outwardly directed portion of said plate and having its opposite end directed at an angle to its body portion for engagement with the lid of the box to force the latter tightly upon the sides and ends of the latter, said latch member also having an outwardly directed portion to embrace the upper outwardly directed portion of the keeper plate and provided with a slot, and a keeper swiveled on the keeper plate and provided with a head to pass through said slot of the latch member and bear against the outwardly directed portion of the latter to lock the lid against accidental opening.
2. The combination with a box provided

with a hinged lid; of a keeper plate, a latch member pivoted to the plate and having one end formed to engage the lid and force it down tightly upon the sides and ends of the box and also having an outwardly directed portion intermediate its ends, and a keeper secured to the keeper plate and having a head for binding engagement with said outwardly directed portion to lock the lid against accidental opening.

3. A keeper comprising a body portion having reduced ends and bent upon itself to form a head and a shank, and a disk fitted to said shank.

In testimony whereof I affix my signature, in presence of two subscribing witnesses.

WILLIAM TISCH.
